TO ALLMANA SVENSKA ELEKTRISKA AKTIEBOLAGET, OF VÄSTERAS, SWEDEN,
A CORPORATION OF SWEDEN.

TIME-LIMIT INDUCTION RELAY.

Application filed January 11, 1923, Serial No. 611,969, and in Sweden December 4, 1922.

In my pending patent application No. 472,848, I have described an inverse time limit relay of the induction type, in which the operating device (any induction disc or the like) is mounted in a pivoted frame which is balanced in such manner that upon a rise of current over a certain value, the frame will be swung under the influence of the induction forces acting upon the disc or corresponding member so as to bring the latter device into engagement with the releasing mechanism of the relay, and thus to initiate the releasing movement proper. In the said application, it has been presupposed that the tangential force acting from the electromagnet to rotate the induction disc has been the force which moves the frame into operative position.

In accordance with my present invention, I accomplish the desired result of moving the induction member into operative position for initiating the releasing movement by causing the said member to be actuated by an induction force depending upon the operating current, but acting in a direction different from the tangential one. This force may for an instant consist of a component of the same force of which a tangential component serves to rotate the induction member (which may be a disc or a cylinder or of some intermediary shape). In most cases it is, however, preferable to derive it from a separate magnetic field, either by providing a magnetic shunt to the driving electromagnet or by using a separate coil traversed by the same current as the electromagnet or by a current proportional thereto. Under the influence of the said force, the induction member is thus displaced in a direction different from the tangential one when moved into its operative position. Hereby the advantage is gained that the induction member can easily be shaped in such way or arranged in such way with respect to the operative flux that the tangential force is increased by the displacement and again reduced when the member is displaced in the opposite direction. Hereby the "creepage" can be entirely prevented and the return movement facilitated without necessitating the use of a detachable connection between the induction member and the releasing mechanism. Instead of a connecting and disconnecting

operation on this point there is employed, so to say, a connecting and disconnecting operation between the induction member and its driving flux.

In the drawing, some forms of the invention are diagrammatically illustrated. Figure 1 shows, in a side view, a relay having a common magnetic field producing a force upon the induction member which is divided into two components, a tangential "driving force" and a "displacing force" perpendicular thereto, and serving to displace the induction members. Figure 2 shows, in a side view, a form in which the displacing force is produced by a separate magnetic field forming a magnetic shunt to the main field. Figure 3 is a corresponding front view. Figure 4 shows a form in which the displacing field, which still forms a magnetic shunt, does not act directly on the induction member, but on a separate member mechanically connected thereto.

In all the forms shown, the induction member consists of a disc 1 moving between the poles of one electromagnet 2, the coil 3 of which is traversed by the current serving to operate the relay. The said induction member is supported in a frame 4, capable of rocking about an axis 5, said rocking movement being limited by a pair of stops 6 between which moves a portion 7 of the frame serving also as a counterweight.

The poles of the magnet 2 exert a tangential driving force on the induction member and for this purpose they are provided, in a well-known manner, with an auxiliary short-circuited winding which embraces a portion of the pole and produces a flux in this portion of different phase from that of the rest. In Figure 1, the said auxiliary winding 8 is arranged obliquely in such manner, that the force acting on the disc 1 will form a certain angle with the tangential direction. Further the disc, in its normal position, has its edge right in front of the poles, so that the action thereon for a certain amount of current in the coil 3 will be smaller than if the whole of the pole faces were covered by the disc. By a suitable counteracting force, which may be provided in a manner as hereinafter described, the rotation of the disc under the influence of the magnet field may be prevented in this position, even if the current rises to the

value for which the relay is intended to operate. On the other hand, at that current value, the radial component of the force acting on the disc from the field should be sufficient to raise the disc and its suspension device so that the disc will cover the whole of the pole surfaces. By the increase in the tangential force hereby gained, it will be sufficient to rotate the disc.

10 The aforesaid counteracting force, which initially prevents the rotation of the disc, is provided, according to Figure 1, by arranging a pinion 9 on the shaft of the disc in permanent engagement with a toothed segment 10, which is mounted on an axis 11 in the frame 4 and has a certain amount of unbalanced weight, which must be surmounted before the rotation can begin. The toothed segment 10 has a projection 12 which, after having been raised through a certain distance, acts upon the contacts of the relays or on corresponding members and performs a releasing action. In this form the engagement between the driving induction member and the releasing mechanism is thus permanent, but it may also be detachable. The downward movement of the toothed segment 10 is limited by stop 13 on the frame 4.

20 30 The permanent engagement between the two main portions of the relay has the advantage over the intermittent one suggested in my pending application No. 472,848, that the length of the movement of the releasing mechanism can be more finely adjusted, as it becomes independent of the pitch of the engaging members. Hereby also the time setting of the relay can be more exact. The "creepage" is prevented, in spite of the permanent engagement, by the fact that the rotating forces acting upon the induction member are normally considerably reduced. The displacement of the induction member into a more active position with respect to the said forces thus corresponds to its bringing into engagement with the releasing mechanism according to my application No. 472,848.

40 Referring to Figures 2 and 3, the electromagnet has two pole pairs, the fluxes of which are parallel to each other. The one pole pair 14 has a short-circuited coil 15, so arranged as to produce a tangential force on the disc 1, while the other pole pair 16 with its coil 17 pulls the disc in a radial direction so as to be more strongly influenced by the pole pair 14. The latter, in analogy with the single pole pair in Figure 1, is placed near the edge of the disc, while the pole pair 16 is arranged opposite a weakened portion of the disc. The weakening, in the form shown, is accomplished by means of perforations 18. Hereby also the induction force is increased as soon as the displacement begins. The further details of the form

correspond closely to those already described with reference to Figure 1.

In both of the forms described, the magnet 2 can also serve as a braking magnet, since it has either a flux or a force component which does not act to rotate the disc.

5 Figure 4 finally shows a form in which the magnetic field serving to pull the induction disc into operative position with respect to the tangential rotating force, does not act directly on the disc, but on a separate metal piece 19 mounted on frame 4 supporting the disc. This field forms a magnetic shunt path 20 of the driving electromagnet 2. In this form a separate braking magnet 21 is used, as the driving field has no braking component.

10 I claim as my invention:

1. In time relays, a rotatable induction member, a movable frame supporting same, an electromagnet having poles exerting a tangential force on said induction member, and other poles on the same electromagnet producing a force for displacing the said induction member.

2. In time relays, a rotatable induction member supported in a movable frame, and an electromagnet having two pairs of poles, one pair arranged to produce a tangential force on said induction member, and the other to produce a force in another direction on said induction member.

3. In time relays, a rotatable induction member, supported in a movable frame, and an electromagnet having two pairs of poles magnetically parallel to each other, one pair of poles arranged to produce a tangential force on said induction member and the other to produce a force on said member perpendicular to the tangential direction.

4. In time relays, a rotatable induction member, an electromagnet having poles exerting a tangential force on said member, a frame supporting same and displaceable in a direction perpendicular to said tangential force, and another pair of poles on the electromagnet acting to displace the frame in said last-mentioned direction.

5. In time relays, a rotatable induction member, electromagnet poles acting to rotate same, and independent means actuated by other poles for displacing the said induction member with respect to said poles, so as to bring more of its material to be traversed by the flux of said poles.

6. In time relays, a rotatable induction member, electromagnet poles acting to rotate same, other electro-magnet poles acting on said member to displace its axis of rotation and to bring more of its material to be traversed by their proper magnetic flux.

7. In time relays, a rotatable induction member, electromagnet poles acting to rotate same, means for displacing said member with respect to said poles so as to increase

the rotating forces acting thereon, a releasing mechanism permanently connected to said induction member, and means for preventing said member from rotating until 5 said rotating forces have been increased by the displacement.

8. In time relays, a rotatable induction member, electromagnetic means acting to displace said member both in a tangential di-

rection and in a direction perpendicular 10 thereto, the means for displacing in said latter direction serving also to brake the rotating movement of said induction member.

In testimony whereof I have signed my 15 name to this specification.

WILHELM HENNING PETERSÉN.
